UNITED STATES PATENT OFFICE

SIMON COOPER, OF BROOKLYN, NEW YORK

SOSTENUTO PIANO

Application filed April 14, 1928. Serial No. 269,963.

This invention relates to electrical sostenuto pianos and has special reference to a sostenuto piano of the general type described in the U. S. Letters Patent granted to me and bearing the number 1,598,056, in that electro-magnetic means are employed for obtaining the sostenuto effect and these means are controlled in their action by a current pulsator which is in turn controlled by the vibrations of the piano string, it being understood that I here refer to a single unit of the complete apparatus since each note on the piano will have its string or strings controlled for sostenuto effect in like manner.

In the study of true sostenuto action by means of electro-magnetic control I have encountered various complexities due to the physical laws pertaining to the result desired to be accomplished and a brief explanation of the action of the several physical forces in the solution of this problem will make clear the value and utility of the present invention.

It is not practically possible to set a string into musical vibration while under such tension as exists in an ordinary piano by merely plucking at the string by electro-magnetic attraction. A vibrating string may, however, have its vibrations prolonged or maintained by properly arranging for magnetic attraction of the string at a definite phase in its vibration and in order to do this it is essential that the plucking or attraction of the string be in synchronism with the motion of the string at the particular zone where the plucking or attraction is applied. Furthermore, the piano string to give full musical value by its vibrations must assume the loops and nodes not only to sound its fundamental note but also to sound the partial tones or over tones which render the note agreeable and give it its proper character. These partial tones or over tones are generated by reason of the imposition of smaller loops and nodes upon the fundamental loops of the piano string. It can now be realized that the pluck on the string must be in exact relation to the motion of the string when the pluck is applied and also that the pluck or attraction must occur

when the particular portion of the string attracted is approaching the electro-magnet and only for that lesser portion of the period that the superimposed or over tone loop at that particular point is also approaching the magnet.

To achieve such result by absolute timing or other control of the electric current energizing the attracting magnet by extraneous means is impractical but by a proper assemblage of operating elements and by having due regard to the properties of materials such synchronism of the magnetic pluck may be controlled in a feasible manner by the motion and position of the string itself and the device disclosed in the present application and which has given satisfactory service may be described in general as follows:—

Since the force of gravity is constant and not affected by change in the properties of materials, I have used this force as the major factor in the means of attaining synchronism of magnetic pluck through the motion of the musical string itself and in the present application of the invention there has been disclosed a pair of electrodes which are mounted in a circuit including a source of electric energy, a switch controlled by the piano key governing the respective note and an electro-magnet disposed close to the string or strings generating the note when vibrated. One of these electrodes rests by reason of its weight upon a bed of granular conducting material, this material in turn resting upon the other electrode which is fastened to a support of low resiliency so that the circuit has a high degree of inertia as compared to the velocity of motion attained by the musical string in sounding the tone. This circuit is put in motion by means of a connection between the circuit and the musical string which is composed of a material which, while resilient to the desired extent, has a total stretch less than the range of motion of the vibrating musical string. It is also to be observed that the force of gravity acting on the free electrode cannot overcome its inertia rapidly enough to impart velocity equal to that of the musi-

cal string when in motion since the distance through which the upper electrode tends to travel is very minute, being only equal to the amplitude of vibration of the string at the point to which connection is made. Therefore, since the force of gravity cannot impart velocity to the electrode equal to that of the musical string when in motion, we have a chain of connections between the high velocity motion of the musical string and the electric contact between the free electrode and the bed of granular conducting material on which it rests, and there results a variation in the conductivity of the circuit. It is now merely necessary to adjust the parts so that the phase of the variations in this circuit are synchronous with the phase of vibration of that portion of the musical string which is affected by the magnetic pluck in order to attain musical sostenuto effect.

With the above and other objects in view as will be hereinafter apparent, the invention consists in general of certain novel details of construction and combinations of parts hereinafter fully described, illustrated in the accompanying drawings and specifically claimed.

In the accompanying drawings like characters of reference indicate like parts in the several views, and:

Figure 1 is a diagrammatic view illustrating one form of the arrangement of the circuit, actuating magnet and controlling pulsator in their relation to a piano string.

Figure 2 is an enlarged detail side elevation of the pulsator showing its relation to a piano string.

Figure 3 is a section on the line 3—3 of Figure 2.

Figure 4 is an enlarged detail elevation of the upper or free electrode of the pulsator.

In the arrangement shown in Figure 1 the parts are illustrated in a purely conventional manner and various parts are omitted as not being necessary to an understanding of the invention. In this figure a piano string 10 is supported in the conventional way on bridges 11 and 12 and beneath this string is a hammer H actuated from the key 17, the connection between the hammer and key being omitted as being of the usual conventional variety and forming no specific part of the present invention. An electro-magnet 13 is fixed in proximity to the string and as near to the zone where the piano hammer H strikes as is found practicable. From the magnet 13 a conductor wire 25 extends to and is connected with the fixed electrode 21 of the pulsator indicated in general at 14. The magnet is also connected by a wire or conductor 24 with one terminal of a suitable source of electric energy here indicated by a battery 15. From the battery 15 a wire 31 leads to one of the

contacts of a switch 16 which is disposed beneath the key 17 so that depression of the key closes the switch. The other contact of this switch is connected to the loose terminal or electrode of the pulsator by a wire 30. The electrode or terminal 21 is fixed on a strip or blade 19 of insulating material and having a suitable degree of resiliency. In order to thus secure the electrode a stud 20 is screwed into the electrode or terminal 21 passes through the blade 19, and has screwed thereon a nut 29 which thus holds the parts together. This blade 19 has one end mounted on a suitable fixed part 32 of the piano so that vibration of the blade may be effected by a loop 18 extending from the free portion of the blade and passing around one or more of the strings 10 which are struck by the hammer H, it being well known that in some instances the note is produced by a single string while in other instances the required note is produced by a plurality of strings tuned in unison. Mounted on the terminal 21 is an insulating casing or cylinder 33 and supported on the terminal 21 within the cylinder is a bed of granular conductive material 22 whereon rests the terminal 23 to which the wire 30 is connected. This terminal 23 is in the form of a metallic sphere and has an equatorial groove 26 wherein is seated an elastic band 27, the parts being so positioned that the terminal rests on the bed 22 centrally of the bed, being held from moving into contact with the wall of the cylinder 33 by means of the band 27 while at the same time being free to move in the cylinder or casing 33 without undue friction. The wire 30 has its end extending into a polar opening or bore 28 and as this wire comes down from above the pulsator its tendency is to maintain the terminal 23 with its equatorial groove in horizontal position.

In the operation when the string 10 is caused to vibrate because of the hammer stroke such vibrations will be communicated to the loop 18 which is composed of wool yarn or silk thread and this will cause the blade or strip 19 extending from the rigid support located in the piano to vibrate. This strip 19 is preferably made of celluloid or other like material and is of such proportions that its return of vibration is less than that of the string 10. Now, since the electrode or terminal 23 rests on the conducting material 22 the vibrations of the blade, due to the inertia of the terminal or electrode 23, have the effect of alternately compressing and decompressing the granular material and thereby alter the effective conductivity of such granular material between the terminals or electrodes 21 and 23 so that pulsations are caused in the electric circuit and the magnetic field due to the electro-magnet 13 is alternately increased and decreased in accordance with the increase and decrease of

the effective conductivity of the granular material.

It will be noted in Figure 2 that three piano strings are depicted and it is well known that the heavy bass notes in the conventional piano are composed of single string, the middle bass notes are composed of double string and the remaining notes are composed of triple strings. The loop 18 can be attached to one of the strings of the note or looped around two or three strings, the purpose for this loop being to convey vibrations to the blade 19.

The free electrode 23 functions best when there is no restraining force upon it and for that reason it is made of a smaller diameter than that of the pulsator 14, but in some instances it has a tendency to contact with the said wall and this results in an unsatisfactory musical tone or foreign sound resulting of the impact of the electrode upon the wall. This is overcome by the application of the flexible ring 27, which also serves to maintain the sphere in a central position. The spherical shape of the electrode 28 permits it to assume a natural position upon the bed of granular material 22 and in the event of its shifting from a central position or its axis shifting from the vertical the same area and the same pressure between it and the granular material is maintained.

When the apparatus is installed as indicated by the above description synchronism between pulsations or undulations of the electric current energizing the electro-magnet and the motion of the string is accomplished by moving the loop 18 along the string until such synchronism is obtained. As the loop contacts with the string near one of its bridge supports, and preferably with the bridge near the striking end of the string, the loop needs to be moved over only a slight distance to determine point for attaining synchronism with the musical vibrations of the string.

There has thus been provided a simple and efficient device of the kind described and for the purpose specified.

It is obvious that minor changes may be made in the form and construction of the invention without departing from the material spirit thereof. It is not, therefore, desired to confine the invention to the exact form herein shown and described, but it is desired to include all such as properly come within the scope claimed.

Having thus described the invention, what is claimed as new, is:

1. In an electric sostenuto piano, a piano string, a source of electric energy, an electro-magnet disposed close to the piano string in circuit with the source of electric energy, a current varying unit in series with the source of energy and electro-magnet, said

unit comprising a lower and an upper electrode and comminuted conducting material confined between them, and means controlled by the vibration of the string and connecting the string and unit to actuate the latter as the string vibrates, said means being composed of a material of low resiliency.

2. In an electric sostenuto piano, a piano string, a source of electric energy, an electro-magnet disposed close to the piano string in circuit with the source of electric energy, a current varying unit in series with the source of energy and electro-magnet, said unit comprising a lower and an upper electrode and comminuted conducting material confined between them, means controlled by the vibration of the string and connecting the string and unit to actuate the latter as the string vibrates, said means being composed of a material of low resiliency, and a vibratile support for said unit having a periodicity of vibration less than that of the piano string.

3. In an electric sostenuto piano, a piano string, a source of electric energy, an electro-magnet disposed close to the piano string in circuit with the source of electric energy, a current varying unit in series with the source of energy and electro-magnet, means controlled by the vibration of the string and connecting the string and unit to actuate the latter as the string vibrates, said means being composed of a material of low resiliency, and a vibratile blade supporting said unit and having one end fixed, said blade having a periodicity of vibration less than that of the piano string.

4. In an electric sostenuto piano, a piano string, a source of electric energy, an electro-magnet disposed close to the piano string in circuit with the source of electric energy, a current varying unit in series with the source of energy and electro-magnet, and means controlled by the vibration of the string and connecting the string and unit to actuate the latter as the string vibrates, said current bearing unit including a pair of terminals, one of which is free for movement solely under the action of gravitation.

5. In an electric sostenuto piano, a piano string, a source of electric energy, an electro-magnet disposed close to the piano string in circuit with the source of electric energy, a current varying unit in series with the source of energy and electro-magnet, and means controlled by the vibration of the string and connecting the string and unit to actuate the latter as the string vibrates, said current bearing unit including a pair of terminals, one of which is free for movement solely under the action of gravitation, said free terminal resting normally on conductive material and being so constructed that alteration of its position relative to such ma-

terial about any axis of the terminal will not alter the conductivity of the electric current.

6. In an electric sostenuto piano, a piano string, a source of electric energy, an electro-magnet disposed close to the piano string in circuit with the source of electric energy, a current varying unit in series with the source of energy and electro-magnet, and means controlled by the vibration of the string and connecting the string and unit to actuate the latter as the string vibrates, said current bearing unit including a pair of terminals, one of which is free for movement solely under the action of gravitation, said free terminal resting normally on conductive material and being so constructed that alteration of its position relative to such material about any axis of the terminal will not alter the conductivity of the electric current, said free terminal presenting in all positions the same area to the medium upon which it rests.

7. In an electric sostenuto piano, a piano string, a source of electric energy, an electro-magnet disposed close to the piano string in circuit with the source of electric energy, a current varying unit in series with the source of energy and electro-magnet, and means controlled by the vibration of the string and connecting the string and unit to actuate the latter as the string vibrates, said means being shiftable longitudinally of the string whereby to obtain synchronism of the variations in the magnetic attraction for the string and the motion of said string.

8. In an electric sostenuto piano, a piano string, a source of electric energy, an electro-magnet disposed close to the piano string in circuit with the source of electric energy, a current varying unit in series with the source of energy and electro-magnet, said unit comprising a lower and an upper electrode and comminuted conducting material confined between them, and means controlled by the vibration of the string and connecting the string and unit to actuate the latter as the string vibrates, said means having a low degree of elasticity.

50 9. In an electric sostenuto piano, a piano string, a source of electric energy, an electro-magnet disposed close to the piano string in circuit with the source of electric energy, a current varying unit in series with the source of energy and electro-magnet, said unit comprising a lower and an upper electrode and comminuted conducting material confined between them, and means controlled by the vibration of the string and connecting the string and unit to actuate the latter as the string vibrates, said means having a low degree of elasticity whereby to dampen the transmission of the string vibrations to the current bearing unit.

65 10. In an electric sostenuto piano, a piano

string, a source of electric energy, an electro-magnet disposed close to the piano string in circuit with the source of electric energy, a current varying unit in series with the source of energy and electro-magnet, said unit comprising a lower and an upper electrode and comminuted conducting material confined between them, and means controlled by the vibration of the string and connecting the string and unit to actuate the latter as the string vibrates, said means having a low degree of elasticity whereby to absorb part of the vibration of the string.

11. In an electric sostenuto piano, a piano string, a source of electric energy, an electro-magnet disposed close to the piano string in circuit with the source of electric energy, a current varying unit in series with the source of energy and electro-magnet, and means controlled by the vibration of the string and connecting the string and unit to actuate the latter as the string vibrates, said means functioning at a lesser period of vibration than the period of vibration of the piano string.

12. In an electric sostenuto piano, a piano string, a source of electric energy, an electro-magnet disposed close to the piano string in circuit with the source of electric energy, a current varying unit in series with the source of energy and electro-magnet, and means controlled by the vibration of the string and connecting the string and unit to actuate the latter as the string vibrates, said unit including a pair of terminals and a bed of conductive granular material carried by one terminal and having the remaining terminal resting thereon by gravity.

13. In an electric sostenuto piano, a piano string, a source of electric energy, an electro-magnet disposed close to the piano string in circuit with the source of electric energy, a current varying unit in series with the source of energy and electro-magnet, and means controlled by the vibration of the string and connecting the string and unit to actuate the latter as the string vibrates, said unit including a pair of terminals and a bed of conductive granular material carried by one terminal and having the remaining terminal resting thereon by gravity, said means connecting the string with the lower terminal whereby the circuit conductivity is varied by the inertia of the upper terminal.

14. A pulsator for use in sostenuto pianos and the like in combination with a vibratory string, comprising a support capable of moderate but substantial vibratory movement and non-synchronously-resonant with the string, a lower electrode thereon, an upper electrode, means retaining the upper electrode for vibratory movement under inertia, and comminuted conducting material between the electrodes.

15. A pulsator for use in sostenuto pianos and the like in combination with a vibratory string, comprising a support capable of moderate but substantial vibratory movement and non-synchronously resonant with the string, a lower electrode thereon, a guide sleeve extending up from the electrode, comminuted conducting material retained by the sleeve upon the electrode, and a second electrode retained by the sleeve with clearance for vibratory movement under inertia and resting on the comminuted material.

16. A pulsator for use in sostenuto pianos and the like in combination with a vibratory string, comprising a support capable of moderate but substantial vibratory movement and non-synchronously resonant with the string, a lower electrode thereon, an upper electrode, means retaining the upper electrode for vibratory movement under inertia, comminuted conducting material between the electrodes, and yieldable means between the upper electrode and its retaining means and preventing rattling contact between them.

17. A pulsator for use in sostenuto pianos and the like in combination with a vibratory string, comprising a support capable of moderate but substantial vibratory movement and non-synchronously resonant with the string, a lower electrode thereon, a guide sleeve extending up from the electrode, comminuted conducting material retained by the sleeve upon the electrode, a second electrode retained by the sleeve with clearance for vibratory movement under inertia and resting on the comminuted material, and yieldable means between the second electrode and the sleeve and preventing rattling contact between them.

18. A pulsator for use in sostenuto pianos and the like in combination with a vibratory string, comprising a support capable of moderate but substantial vibratory movement and non-synchronously resonant with the string, a lower electrode thereon, an upper electrode, means retaining the upper electrode for vibratory movement under inertia, and comminuted conducting material between the electrodes, the upper electrode being substantially spherical and having a shallow lower segment imbedded in the comminuted material affording current flow variations by lateral movement of said electrode.

19. A pulsator for use in sostenuto pianos and the like in combination with a vibratory string, comprising a support capable of moderate but substantial vibratory movement and non-synchronously resonant with the string, a lower electrode thereon, a guide sleeve extending up from the electrode, comminuted conducting material retained by the sleeve upon the electrode, and a second electrode retained by the sleeve with clear-

ance for vibratory movement under inertia and resting on the comminuted material, the second electrode being substantially spherical and having a shallow lower segment imbedded in the comminuted material affording current flow variations by lateral movement of said electrode.

In testimony whereof I affix my signature.

SIMON COOPER.
